(57) **CLAIM**

The ornamental design for a pest eradication device, as shown and described.

DESCRIPTION

FIG. 1 is an isometric view of a pest eradication device showing my new design in a collapsed state.

FIG. 2 is an isometric view of the pest eradication device shown in an open state.

FIG. 3 is a top view of the pest eradication device.

FIG. 4 is a front view of the pest eradication device.

FIG. 5 is a right side view of the pest eradication device.

FIG. 6 is a left side view of the pest eradication device.

FIG. 7 is a rear view of the pest eradication device; and,

FIG. 8 is a bottom view of the pest eradication device.

The broken lines are for illustrative purposes only and form no part of the claimed design.
